FIG 6

J. M. Johnson

UNITED STATES PATENT OFFICE.

JULIUS STROMEYER, OF PHILADELPHIA, PENNSYLVANIA, AND WILLIAM W. MORTON, OF CAMDEN, NEW JERSEY.

BRAKE-SHOE.

No. 866,085.

Specification of Letters Patent.

Patented Sept. 17, 1907.

Application filed October 15, 1906. Serial No. 338,921.

To all whom it may concern:

Be it known that we, JULIUS STROMEYER, of the city and county of Philadelphia and State of Pennsylvania, and WILLIAM W. MORTON, of the city and county of Camden and State of New Jersey, have invented an Improvement in Brake-Shoes, of which the following is a specification.

Our invention has reference to brake shoes and consists of certain improvements which are fully set forth 10 in the following specification and shown in the accompanying drawings, which form a part thereof.

The object of our invention is to provide a construction of brake shoe which shall be easily and cheaply made and repaired, and our object is further, to provide 15 a braking surface having its surface presenting a series of gritty portions surrounded and interspaced with cast iron portions whereby the former automatically provide material to maintaining an effective resisting surface to the iron which presses against the 20 tire or tread of the wheel and thereby greatly increases the braking action of the shoe of given size over what would be the case of a shoe when made of iron alone.

Our invention consists of a carrier for the shoe having a front part slotted in the middle and combined 25 with a shoe having its rear recessed and provided with shoulders to receive the front part of the carrier and also a rearwardly extending lug passing through the slot, and a locking pin extending through the lug immediately back of the said slotted part of the carrier.

Our invention also consists in providing a cast iron 30 shoe with a series of chambers opening to the friction surface of the shoe, combined with fillings of a mixture of sand or other gritty substance and a binder forming a comparatively hard composition immovably held in 35 the iron of the shoe and adapted to be slowly disintegrated under wear to liberate the sand and permit it to act upon the surface of the iron of the shoe to increase its coefficient of resistance under frictional contact.

Our invention further consists in forming the 40 chambers of greater area at the rear than at the front or otherwise with retaining parts, when combined with the filling of blocks formed of gritty substance and a binder so that rough usage can never dislodge the 45 gritty block or material and a proper presentation of friction surface is always assured.

Our invention also comprehends details of construction, which, together with the features above specified, 50 will be better understood by reference to the drawings, in which:

Figure 1 is a sectional side elevation of a brake shoe embodying our invention; Fig. 2 is a front elevation of the same; Fig. 3 is a front elevation of the carrier with the shoe removed; Fig. 4 is a perspective view of one 55 the shoe removed; Fig. 5 is a perspective view of one

of the gritty blocks employed in the shoe; Fig. 6 is a sectional view showing a modified construction with respect to the application of the gritty substance.

A is the carrier and has hub portion E having a hole for attachment to a brake shaft or otherwise. The front portion C of the carrier is preferably formed like a curved plate and is connected to the hub portion by arms C', leaving an open space C² between the hub and front plate. The curved front plate is slotted at its middle at D for the reception of a lug from the shoe or 60 brake block. Where the brake shoe is to be used on wheels of small diameter such as car wheels the front plate C would be curved, but when it is to be used on wagons in which the wheels are of large diameter, then the front plate C may be made with little or no curvature. The shoe B is formed of cast iron and is curved on its back to fit the curvature of the part C of the carrier when so made, and is also provided with shoulders F, F' which fit over the ends of the said curved part of the carrier so that it cannot shift up or down on the 65 carrier. The rear part of the shoe at about its middle, is provided with a lug G which projects through the slot D in the curved part C of the carrier and is held in place by a cotter pin H which passes through a hole in the lug and rests against the rear face of the said 70 part C of the carrier. We also prefer to make the lug sufficiently long that its rear shall just reach the hub E of the carrier to give additional strength in case of such excessive strain as might spring the carrier. By this construction it is evident that shoe may be quickly 75 applied or removed and no material strain or wear comes upon the cotter pin. It will also be observed that, in the form shown, the shoes are reversible and may also act equally well on car trucks when arranged in front or to the rear of the wheels. 80

The shoe is formed on its braking surface with a series of deep chambers J which are preferably arranged on a diagonal as shown in Fig. 2. These chambers we prefer to form of greater area at their inner ends than at the braking surface, and also, it is 85 most desirable that this increase in area shall be gradual from the braking surface inward for reasons to be explained hereinafter. We fill the chambers with blocks K of gritty material such as sand and a cement or binder. This mixture is placed in the chambers 90 in a plastic condition so as to completely fill them and when hardened is permanent and adapted to withstand great jarring without becoming loose. The rear of the chambers are closed and the metal at the back of the shoe is continuous and sustains the gritty 95 blocks, whereas at the front it is grid like. The blocks of gritty material are made as wide as possible so as to provide a series of sand supplying portions alternating with transverse cast iron portions B. 100

In operation, the sand gradually breaks away from 110

the cement or binder and lodges between the cast iron portion B of the shoe and the wheel and by being embedded in the iron makes it more effective as a braking member. Aside from directly acting to increase the friction by its immediate presence, the sand further so abrades the surfaces of the shoe and wheel that a more effective braking resistance is secured by the shoe upon the wheel than where iron alone is employed.

10 It is essential that the gritty substance shall be capable of being pulverized between the brake shoe and the wheel so as not to produce any material grinding of the wheel. Any substance which would produce such grinding would be totally unfit for use 15 in the blocks K. Substance such as emery and corundum are not suitable, but sand, crushed flint, quartz granite, glass and similar substances which while offering material resistance are capable of being pulverized between the shoe and wheel may be employed 20 in our invention with excellent results. The binder would usually be of hydraulic cement, but other binders such as asphaltum, fire clay, glue rosin, and liquid glass for example, may be employed if so desired. The binder should be only in such quantity 25 as is necessary to hold the sand or gritty material together, since it is desired to have as much sand or its equivalent in each block as possible. By employing a binder, the sand cannot jar out and become lost, and it also enables the sand to be carried without 30 depending upon the action of gravity to hold it in place. Moreover, by cementing the sand in position, it is evident that my shoe may be reversed and perform its function equally well.

While we prefer the form of the chambers shown in 35 Figs. 1 and 2 and as indicated by the block Fig. 5, it may be made of other shapes as indicated, for example, in Fig. 6, in which the chamber has the obstructing part J' which prevents the gritty blocks K' working loose. In some cases, we have found it possible 40 to use the chambers of the same sectional area at all depths, in which case the roughness of the iron walls

was sufficient to hold the gritty blocks in place, hence, while we prefer the form of chambers shown in Figs. 1 and 2, I do not confine myself thereto.

The general form of the shoe may be modified to 45 suit the car or other vehicle wheel and likewise the carrier may be changed to adapt it to any particular use without departing from the spirit of the invention.

Having now described our invention what we claim as new and desire to secure by Letters Patent, is: 50

1. In a brake shoe, a carrier formed with a forward slotted plate and an open space to the rear thereof, combined with a shoe having shoulders at top and bottom fitting over the ends of the slotted plate and also having a rearwardly extending lug projecting through the slot, and a transverse retaining pin extending through the lug immediately at the rear of the slotted plate and arranged in the open space of the carrier. 55

2. In a brake shoe, a carrier formed with a rear hub and a forward slotted plate and an open space to the rear of the plate and between it and the hub, combined with a shoe having shoulders at top and bottom fitting over the ends of the slotted plate and also provided with a rearwardly extending lug projecting through the slot and having its end brought close to the hub so that it may act 60 as an abutment, and a transverse retaining pin extending through the lug immediately at the rear of the slotted plate and arranged in the open space of the carrier. 65

3. In a brake shoe, the shoe portion made of cast iron and having a series of diagonal chambers opening to the 70 braking surface so as to form a grid like structure, the said diagonal chambers overlapping each other combined with gritty blocks of material composed of sand and hydraulic cement and completely filling and held in the diagonal chambers. 75

4. In a brake shoe, a shoe of cast iron having its braking surface provided with a series of chambers, combined with a filling for said chambers consisting of a mixture of a gritty substance composed of sand and hydraulic cement which is applied in the plastic state and allowed to set 80 and become hard.

In testimony of which invention, we hereunto set our hand.

JULIUS STROMEYER.
WM. W. MORTON.
